Primary Examiner—Ted Shooman*Assistant Examiner*—Nanda Bondade*Attorney, Agent, or Firm*—Abelman, Frayne & Schwab**[57] CLAIM**

The ornamental design for a doll having a bagel-shaped head with bagel-shaped trimmings, as shown and described.

DESCRIPTION

FIG. 1 is a front elevational view of a doll having a bagel-shaped head with bagel-shaped trimmings showing my new design, the rear elevational view being a mirror image;

FIG. 2 is a right side elevational view thereof, the left side elevational being a mirror image;

FIG. 3 is a top plan view thereof; and,

FIG. 4 is a bottom plan view thereof.

The broken line showing of the in-line skates on FIG. 1 is for illustrative purposes only and forms no part of the claimed design.
